UNITED STATES PATENT OFFICE

FRANK WISNIEWSKI, OF READING, PENNSYLVANIA

DETENTION APPLIANCE FOR FIRE-ALARM BOXES

Application filed August 2, 1928. Serial No. 296,995.

This invention relates to fire-alarm systems and more particularly to the station call or alarm-boxes of such systems. It aims to provide improved means by which persons sounding alarms will be caught and detained at the alarm-box until released, thus serving as a deterrent against the sounding of false alarms.

The invention will be best understood upon description with reference to the accompanying drawings wherein an embodiment thereof is shown applied to an ordinary fire-alarm box such as seen on any street corner.

In said drawings:

15 Fig. 1 is a front elevation illustrating the invention in application to a fire-alarm box;

Fig. 2 is a side elevation showing part of the appliance housing broken away;

Fig. 3 is a sectional elevation taken on the line 3—3 of Fig. 2;

Fig. 4 is a sectional elevation taken on the line 4—4 of Fig. 1; and

Fig. 5 is a sectional plan view on the line 5—5 of Fig. 2.

25 The illustrative device is represented in application to an alarm-box 6 of a type commonly in use. By slight modification of parts, it is applicable to any type of fire-alarm telegraph embodying manually operable means for closing an electric circuit to sound an alarm at a fire station.

In general, the device or appliance is contained within a housing-member hinged to the front of an alarm-box in place of the usual cover-plate or door. In this instance the housing is formed by an open-backed casing 7 hinged with its back to the front panel of the alarm-box and carrying an ordinary latch-lock 8 to prevent unauthorized opening for access to parts within.

In the front wall or face of said casing, an opening 7^a is provided for insertion of a person's hand to grasp and operate means for closing the alarm circuit. Over this opening, a flap-door 9 is hinged and provided

with a turn-handle 9^a by which it may be quickly released and raised with one hand while the other hand is inserted through the opening for the purpose stated.

Opposite said opening within easy grasp 50 and manipulation of the hand inserted therethrough, a handle 10 is shown on a swivel pin or shaft 10^a extending through a back-plate 7^b of the casing and carrying a member by which to effect closing of the alarm circuit 55 within the alarm-box when said handle is turned. In this instance the handle is turned in a counter-clock-wise direction through an arc of approximately ninety degrees. A stop-pin 11 prevents it being turned in the opposite direction.

Said handle is normally held against turning by a spring-pressed plunger 12 movable in guides 10^b thereon and projecting into a recess 7^c in the aforesaid back-plate of the 65 casing. Said plunger is shown pivotally connected to one end of a link 13 which is swiveled on the handle and pivotally connected at its other end with a push-pin 14, the latter being similarly movable in guides 10^c on the 70 handle and carrying a plate 14^a for movement by finger pressure. By this arrangement, the aforesaid plunger will obviously be retracted against its spring tension so as to release the handle for turning movement 75 when the plate 14^a is pressed by the thumb of the hand grasping the handle.

The member carried by the swivel pin or shaft 10^a for closing the alarm circuit (within the alarm-box proper) when the aforesaid 80 handle 10 is turned is represented by a length-adjustable arm 15 which swings with turning movement of the handle to strike and move or engage a contact closure-member (not shown) so as to give the alarm at a fire 85 station. As the arrangement of parts for closing the circuit may vary in different types of alarm-boxes, and inasmuch as the circuit-closure mechanism is not subject-matter of the present invention, it is unnecessary to 90

describe this feature further than to state that the circuit is closed or caused to be closed by the aforesaid arm or equivalent element when the hand-operable means is turned. It will therefore be appreciated 5 that the invention is applicable to any type of fire-alarm box wherein the circuit is closed by movement of a handle or lever grasped by the person sounding the alarm.

10 In certain types of alarm-boxes, notably the older types, the hand operable means for sounding the alarm may act directly upon a member movable to close the circuit. In so far as the present invention is concerned, it is of little consequence whether the circuit is closed by a handle or lever or by a part moving therewith, as in the present example. In either event the arm or wrist of a person sounding the alarm will be caught within 15 the casing so as to detain the person until subsequently released by a key carried by firemen or police arriving at the box. The means by which this is accomplished will now be described.

20 A normally concealed slide-plate 16 is arranged within the casing for movement behind and across the aforesaid opening 7^a therein, so as to reduce or restrict said opening sufficiently to prevent withdrawal of the hand of a person operating the above described alarm sounding means. Said plate is movable between guides 17 disposed tangentially of the opening on diametrically opposite sides thereof. In this instance the 25 plate is formed with an arcuate edge conforming substantially with the edge of the opening so as to reduce the latter to elliptical shape when moved thereacross. A rack-bar or portion 16^a is provided on the face of the slide for a purpose to appear presently.

30 Supported in the casing walls or brackets, a rocking rod 18 is arranged at substantially right angles to the movement planes of the slide-plate 16 and alarm handle 10 respectively. On opposite ends of said rod, levers 19 and 20 are fixed at inclination to swing with rocking movement of the rod. The lever 19 extends across the longitudinal center line of the slide-plate and is formed with an elongate slot 19^a in its free end through 35 which a pin 16^b on said line of said plate extends. The lever 20 is pivotally connected with one end of a link 21 having opposite end pivotal connection with a crank-pin 22 on the aforesaid alarm handle.

40 By such arrangement, turning movement of the handle to close the alarm circuit will occasion a pulling swing on the lever 20 so as to rock the rod 18 and thereby swing the lever 19 to quickly move the slide-plate across the hand opening in the casing and prevent withdrawal of the hand. On return movement of the handle, the reverse action will 45 obviously take place to force the slide to normal position.

When said plate is thus moved across the hand opening, its rack-bar portion 16^a is engaged by a dog-member 23 preventing reverse movement thereof and consequently of the alarm handle also until disengaged by lock means. Said dog-member is fixed on a rockable rod 24 supported in the casing wall or brackets behind the slide. It is held normally adapted to engage the rack-bar of the slide by a spring 25 acting on one arm of an angular lever-member 26 having its other arm secured to or in the aforesaid rod.

50 The spring-tensioned arm of said lever-member is shown acted upon also by the key-moved plunger of a lock 27 so as to swing it for rocking the rod sufficiently to disengage the dog-member from the rack-bar portion of the slide, thereby permitting the alarm handle to be turned to normal position forcing return movement also of the slide to release the operator's hand, whereupon the lock plunger is retracted to allow back rocking of the rod and dog-member under action of the aforesaid spring.

55 As the invention may be applied to alarm-boxes of different types by making minor changes in the form, construction and arrangement of certain parts without departing from its spirit and scope, the appended claims are not intended to be limiting to the 60 specific construction shown and described.

Having thus described my invention, what I claim as new and desire to secure by Letters Patent of the United States is:

65 1. An appliance for the call-box of a fire-alarm telegraph embodying hand-turnable means controlling the same and having an opening through which the hand of an operator is inserted to operate said means, a slide-plate, means supporting said plate for slide movement restrictively over said opening in the box for confining the wrist of a person operating the hand-turnable means, means connecting said hand-turnable means with said slide-plate whereby the turning movement in opposite directions of the former is converted to slide movement in corresponding opposite directions of the latter, means holding the slide-plate in position restricting the aforesaid opening when moved thereover, and lock-control means for operating said holding means to release said slide-plate for return to normal non-restricting position on reverse operation of said hand-turnable means so as to liberate the wrist of the operator.

70 2. In combination with a fire-alarm box having hand-turnable means operable to close a circuit of an alarm telegraph and an opening through which the hand of an operator is inserted to operate the same, a slide-plate, means supporting said plate for slide movement restrictively over said opening to confine therein the wrist of a person operating said hand-turnable means, means con-

necting said hand-turnable means with said slide-plate whereby the turning movement of the former in opposite directions is converted into slide movement of the latter in correspondingly opposite directions, ratchet means preventing return movement of the slide-plate when moved in one direction over the opening, and lock-control means operable to release said ratchet means so as to permit return movement of the slide-plate and liberate the operator upon his moving the hand-turnable means back to normal position.

In testimony whereof I affix my signature.
FRANK WISNIEWSKI.
